[57] CLAIM

The ornamental design for a door edge pad, as shown and described.

DESCRIPTION

FIG. 1 is a top, front, right perspective view of the door edge pad of the present invention;

FIG. 2 is a top plan view of the door edge pad shown in FIG. 1, the bottom of the door edge pad being a mirror image of the top;

FIG. 3 is a side elevational view of the door edge pad shown in FIG. 1, as seen from the right-hand side of FIG. 1, the left side of the door edge pad being a mirror image of the side shown;

FIG. 4 is a front elevational view of the door edge pad shown in FIG. 1; and,

FIG. 5 is a rear elevational view of the door edge pad shown in FIG. 1.
